UNITED STATES PATENT OFFICE

JACOB W. BEHRENDT, OF SAN FRANCISCO, CALIFORNIA

BOTTLE

Application filed May 5, 1930. Serial No. 449,765.

This invention relates to bottles as used particularly in connection with medicines and it has for its objects a special formation of the bottle neck and a closure therefor which 5 will be better adapted to use with liquid medicines and aid in the accurate dispensing of the same and transferring from bottle to bottle.

Also such a bottle which will have a screw 10 cap yet be free from the objections to screw cap bottles when applied to pharmacists' use, and which will avoid contamination of the medicament with the cap, or its tendency to run down over the threads of the bottle when 15 pouring the liquid therefrom.

In the drawing accompanying this application the figure is a front elevation of a glass bottle with the neck and sealing cap shown in section so as to clearly show the im- 20 proved construction.

In further detail the body of the bottle is shown at 1 and a cap 2 screwed over its neck. This cap is of tubular form and is made of non-corrodible metal or of some non-metallic substance like celluloid, vulcanite, baki- 25 lite, etc. It is flat on top, threaded at its lower end at 3 and formed with a slightly enlarged recess at 4 adjacent its top so as to receive and retain a tightly fitting disk 5 30 of resilient sealing material such as a cardboard or cork disk preferably covered on its underside with a sheet of paraffined paper, cellophane, or the like as at 6, the covering paper being wrapped over the edges of the disk as indicated, and for some uses I prefer- 35 ably cement the disk in place in the cap.

This cap in combination with the particular form of the bottle neck is what constitutes my invention and it will be observed 40 that the tubular cap extends straight down to just clear the outer lip 7 of the bottle, that this lip 7 is reduced to a relatively thin-cornered edge so as to make it possible to pour out a single drop if desired, also that the 45 outer edge of the lip is slanted downwardly from the upper end of the neck which is provided with a substantially flat space at 8 against which the disk seats, and that the inside throat of the bottle rounds out smooth- 50 ly to this flat spot, while the inside of the

neck continues downward in a substantially unbroken curve to the interior of the bottle. This internal formation makes it possible to precisely control the flow of the liquid.

Another feature of great importance is the 55 inward curve of the outside of the neck at 9 for a relatively long distance above the threads with a minimum length of substantially half the diameter of the lip whereby all tendency of back-flow of the liquid is prevented and the bottle may easily be balanced on the edge of a beaker, measuring glass or other bottle in accurate dispensing of medicants therefrom.

The upper portion of the inside of the 60 neck is slightly tapered at 10 to suit a standard cork in case the cap becomes lost or injured.

As an aid to screwing or unscrewing the 65 cap it may be provided with fine flutes 70 around its exterior as at 11.

At first thought my bottle as above de- 75 scribed might be thought to vary but little from any ordinary screw cap bottle, but upon reflection it will be seen to be an im- proved combination which has been a plain unmet requirement in the pharmacist's laboratory for years, as all attempts to introduce screw-capped bottles have thus far met with disfavor because—

1. The bottles had no pouring lip.
2. The former construction prevented the use of a thin pouring lip.
3. There was no flat top for sealing prop- 80 erly against a disk.
4. There was no hooked portion at a dis- tance sufficiently below the pouring edge for 85 balancing the bottle upon the rim of a receiv- ing bottle or vessel.
5. The threads ran clear up to the top of 90 the neck or were so high up as to cause the liquid to run back upon them so as to dirty the whole bottle and cause corroding of the lid.

An examination of the shelves of a dis- 95 pensing pharmacist this very day corroborates the above, and the stock bottles pro- vided with screw caps all suffered from the objectionable features above mentioned.

Therefore, as my bottle is the outcome of 100

much experimenting in this field of work and is a practical, simple, perfect sealing and perfect pouring bottle with dispensing lip and with a plain balancing neck above the 5 threads avoiding any run-back of liquid and with a neck which is easily wiped off to keep it clean so that no liquid will come in contact with the cap to corrode same if of metal, and pharmacists and physicians to whom it has 10 been shown are enthusiastic about it, I believe the combination to be new and useful and to fill a decided requirement in bottles for the purpose intended.

I claim:

- 15 1. A bottle having a pouring neck and an outwardly directed pouring lip around its upper end, threads around the neck at a point spaced below the pouring lip, a relatively long unthreaded portion between the 20 lip and the threads, said unthreaded portion being curved inwardly to smaller diameter to form a balancing neck.
- 25 2. A bottle having a pouring neck and an outwardly directed pouring lip around its upper end, threads around the neck at a point spaced below the pouring lip, a relatively long unthreaded portion between the 30 lip and the threads, said unthreaded portion being curved inwardly to smaller diameter to form a balancing neck, the extreme upper edge of said neck being substantially flat to contact a sealing disk.
- 35 3. A bottle having a pouring neck and an outwardly directed pouring lip around its upper end, threads around the neck at a point spaced below the pouring lip, a relatively long unthreaded portion between the 40 lip and the threads, said unthreaded portion being curved inwardly to smaller diameter to form a balancing neck, the extreme upper edge of said neck being substantially flat to contact a sealing disk, and the upper edge of 45 said pouring lip being slightly lower than the flattened upper edge of the neck.
- 50 4. A bottle having a pouring neck and an outwardly directed pouring lip around its upper end, threads around the neck at a point spaced below the pouring lip for screwing a closure cap over the end of the 55 neck, a relatively long unthreaded portion between the lip and the threads, said unthreaded portion being of smaller diameter than the lip and with a minimum length from the lip to the threads of substantially half the diameter of the lip.

JACOB W. BEHRENDT.
